UNITED STATES PATENT OFFICE

DAYTON HERSCHEL DANLEY, OF LEBANON, INDIANA

ACETYLENE-GAS GENERATOR

Application filed October 5, 1927. Serial No. 224,214.

This invention is an improvement in acetylene gas generators of the type shown in my Patent 1,569,722, dated January 12, 1926, and its principal object is to provide an acetylene gas generator which is easily portable and will produce an ample volume of gas to supply any torch tip, and is as economical as an acetylene tank gas generator.

A further object is to provide a portable acetylene generator in which the operator will have full control of generation at all times by either opening or closing the valve on the torch.

A further object is to provide a generator in which generation of gas will be self controlled by the natural laws and gravity of water and gas under pressure, and does not depend on springs, diaphragms, clockwork or other mechanical parts that easily get out of order.

I will describe the invention as embodied in the generator shown in the accompanying drawings, which illustrates one practical commercial embodiment of the invention; and summarize in the claims the essential features of the generator and novel combinations of parts therein for which protection is desired.

In said drawings:

30 Figure 1 is a side elevation partly in section of a complete generator showing the parts in position for loading the carbide magazine;

35 Fig. 2 is a similar view showing the magazine loaded and lowered into the water to start generation;

Fig. 3 is a similar view showing how accumulated pressure will cause stoppage of generation of gas;

40 Fig. 4 is a similar view showing how the generator will rapidly generate gas to supply an overcharge or excess demand therefor.

Fig. 5 is a detail view of the lower end of the carbide magazine.

45 Fig. 6 is a detail view of the magazine support.

The generator shown in the drawings comprises a closed tank 1 which has a top 1a from which rises a contracted and preferably

centrally disposed cylindrical neck member 2.

The tank is provided with a drain opening at bottom closed by a suitable screw plug 1b. The tank has an overflow opening in its side 55 at the normal water level in the tank, which opening may be closed by a screw plug 1c. When the tank is to be used the plug 1c should be removed and water supplied to the tank until it overflows at the opening, 60 then this opening should be closed by the plug 1c. If desired ordinary drain cocks could be used in place of plugs 1b and 1c.

The member 2 extends through the top 65 into the tank and the lower portion 2a of the neck member in the tank is outwardly and downwardly flared as shown.

The upper end of the neck 2 may be tightly closed by any suitable means, preferably by use of a cover 2b secured to the neck by a 70 yoke 2c and clamping screw 2d in the well known manner.

The lower portion 2a of the neck extends considerably below the normal water level in the tank and its lower end is sealed by the 75 water in the tank.

The space within the neck and above the water forms a gas generating chamber A. The space within the tank above the water level and exterior to the portion of the neck 80 within the tank forms a compression chamber B, and the gas pressure in this chamber regulates or controls the generation of gas in the chamber A as hereinafter explained.

The upper end of chamber B is controllably connected with the upper portion 85 of chamber A preferably by means of a pipe 3 which opens into chamber B through the top 1a and communicates with the chamber A near the top of the neck as shown in the drawings.

The passage of gas through this pipe may be controlled and cut off by a manually operable valve 3a. This valve is operated as hereinafter explained in starting the apparatus, and in controlling the operation 90 thereof.

Arranged within the lower portion 2a of the neck is a carbide holder or magazine, which preferably consists of a cylinder 4b to the lower end of which are attached vertically 100

disposed parallel metal rods 4a, the lower ends of which are inturned and converge on radial lines, as shown in Fig. 5. These rods will retain carbide in the magazine while permitting free access of water thereto. The rods 4a are preferably brazed to the cylinder 4b but may otherwise be secured thereto. The lower ends of such of the rods as extend to the axial line of the magazine may be also brazed or otherwise fastened together.

The magazine is provided with a suitable cover 4r. Preferably this cover has a depending flange entering the top of the cylinder—and provided with key slots 4p adapted to engage rivets 4o brazed in the upper end of the cylinder in position to be engaged by the key slots in the cover flange, as shown in Fig. 2. These key slots and rivets lock the cover 4r to the magazine. The cover has a handle 4s by which it can be turned or lifted, and when the cover is locked to the magazine, as in Fig. 2, the entire magazine can be lifted by and with the cover by means of the handle 4s. The cylinder 4b is of less diameter than the neck and can move vertically therein. The carbide magazine is adapted to contain carbide in any suitable form. Preferably I employ lump or cake carbide; and as carbide manufacturers claim that the larger the carbide cakes the greater the gas yield per pound of carbide, the magazine is designed to use carbide, compressed in large cakes. Lump carbide, size $3\frac{1}{2}$ inches by 2 inches will also give excellent results.

The carbide magazine may be supported and adjusted vertically in the neck by any suitable means. Preferably the lower end of the magazine is supported upon a metal cage or basket 4 (see Fig. 6) attached to the upturned end 4d of a vertical rod 4c which extends into the tank through an opening in the top 1a. The rod 4c extends through the chamber B exterior to part 2a of the neck and at a point below the part 2a the extremity 4d of the rod is bent upwardly and enters the part 2a of the neck, and the lower or basket portion 4a of the magazine rests thereon.

Suitable means should be provided to prevent the escape of gas from chamber B around the rod 4c. As shown a tube 4f surrounds the vertical portion of the rod 4c within the chamber B, said tube being gas tightly connected to the top 1a at its upper end and extending below the water level in the tank so as to be always water sealed.

The rod 4c is provided at its upper end with a head or handle 4g which has a portion projecting inwardly toward the neck and adapted to be engaged with any one of a series of notches in a holder plate 4j attached to the adjacent side of the neck 2. By shifting the rod to engage the head 4g with upper or lower notches in the plate 4j the carbide magazine can be correspondingly raised or lowered within the neck and tank. The

notches in the plate 4j are so located and spaced with reference to the normal water level in the tank, that the operator will know by the point of engagement of the handle 4g with the plate 4j the exact position of the carbide magazine in relation to the normal water level in the tank.

Upon the tank at one side of the neck is mounted a gas washer 5 which may be of any suitable type. Preferably this washer is adapted to contain water, the level of which is regulated by an opening closed by a plug 5a; and the washer may be drained through an opening closed by a plug 5b.

The washer communicates with the gas chamber A preferably by means of a pipe 5c which is connected to the neck 2 near the upper end thereof and near the top of the washer, and said pipe extends down into and below the level of the water in the washer; so that gas entering the washer will pass through the water therein. This gas inlet pipe 5c may be provided with a check valve 5v on its lower end to prevent back flow of gas or water from the purifier into the chamber A.

The upper end of the washer is provided with a draw-off cock 5e which may be connected in the usual manner to the burner or tip to which the gas is to be supplied.

The generating chamber A is preferably provided with a pressure gauge 6 preferably connected to the upper end of the neck 2. The compression chamber B is preferably provided with a pop or safety valve 7, preferably attached to the top 1a of the tank. The tank may be provided with an agitator 37 in its bottom, which may be constructed and operated as described in my aforesaid Patent No. 1,569,722, and it is therefore unnecessary to fully illustrate or describe the same herein.

Operation

When it is desired to charge the generator with carbide, the carbide magazine is raised above the normal water level in the tank to the position shown in Fig. 1. The magazine may then be removed from the neck, and its cover 4r removed, and the magazine filled with carbide. The cover 4r is then replaced and the magazine put back in the neck. To hold the magazine in raised position the handle 4g is engaged with the uppermost notch in the plate 4j. After the magazine is charged and replaced the cover 2b is gas-tightly closed. The carbide magazine should be held above the water level, as in Fig. 1 whenever the generator is to be charged with carbide, or while lowering the pressure.

Whenever the generator is charged, a mixture of acetylene and air is produced at first. For best results this should be drawn off before the torch is lighted.

When it is desired to start generation of gas

the magazine will be lowered to the position shown in Fig. 2 so that the cage is partly submerged and water contacts the carbide in the lower portion of the magazine.

5 The magazine is lowered into the water as in Fig. 2, by engaging handle 4g with the second notch in plate 4j. This starts generation of gas and pressure is thus created in chamber A. The pressure control valve 3a being closed generation of gas will stop at about two (2) pounds or less pressure in chamber A. This pressure is sufficient to force the water in chamber A down below the carbide in the magazine as indicated in 10 Fig. 3, thus stopping generation of gas.

After this initial generation of gas the required pressure for operating any make of torch or any size of tip may be obtained when desired as follows: To increase the pressure in chamber A the pressure control valve 3a should be first opened so as to connect the generating chamber A with the compression chamber B. This equalizes the gas pressures therein and allows the water in the two 25 chambers to again come to the same level (as in Fig. 1) and the water rising in the generating chamber again reaches the carbide in the magazine, and generation of gas proceeds. When the pressure in chamber A reaches about one pound below that desired, the valve 3a should be closed and the generation of gas will continue at such pressure until the outflow of gas from chamber A is checked, whereupon accumulated pressure 35 will leave the water in said chamber, as in Fig. 3 and generation will cease until the pressure is relieved.

To lower the pressure, the carbide magazine is raised above the water level, as shown 40 in Fig. 1; and the pressure control valve 3a opened and gas drawn off until the pressure in chamber A is about one pound below the desired pressure; then valve 3a should be closed and the carbide magazine again lowered to contact the carbide with the water (Fig. 2).

When the generator is generating acetylene fast enough to operate an extra heavy welding tip the water level in the generating 50 chamber A will be raised so as to act on more carbide as indicated in Fig. 4. When the torch is being operated full blast, if the torch is shut off, the water level inside the generating chamber A is almost instantly lowered by the pressure building up in said chamber 55 and forcing the water below the carbide (Fig. 3) then the carbide dries off. The water will hold its position under such pressure just below the lower end of the carbide magazine as in Fig. 3.

Perfect operating conditions are obtained with a pressure range of from one to ten pounds. The pressure should not be raised above ten pounds in the ordinary apparatus.

65 The carbide magazine may be removed

from the neck at any time; making it perfectly safe to transport the generator and the carbide in the magazine can be used later by replacing the carbide magazine in place.

The generator will produce gas at an almost absolutely uniform gas pressure regardless of the rate at which the gas is being drawn off, due to the fact that the slightest variation in gas pressure in the generating chamber instantly varies the water level, and as the carbide magazine is stationary, variation in water level determines the amount of carbide that is immersed, and the water under the gas pressures automatically accurately adjusts itself to supply gas as needed. 70 This also gives the operator full control of generation at all times by either opening or closing the valve on the torch or tip; and this also eliminates the danger of over generation by over supply of carbide which is common to 75 the ordinary generators.

After this initial generation of gas the required pressure for operating any make of torch or any size of tip may be obtained when desired as follows: To increase the pressure in chamber A the pressure control valve 3a should be first opened so as to connect the generating chamber A with the compression chamber B. This equalizes the gas pressures therein and allows the water in the two 25 chambers to again come to the same level (as in Fig. 1) and the water rising in the generating chamber again reaches the carbide in the magazine, and generation of gas proceeds. When the pressure in chamber A reaches about one pound below that desired, the valve 3a should be closed and the generation of gas will continue at such pressure until the outflow of gas from chamber A is checked, whereupon accumulated pressure 35 will leave the water in said chamber, as in Fig. 3 and generation will cease until the pressure is relieved.

To lower the pressure, the carbide magazine is raised above the water level, as shown 40 in Fig. 1; and the pressure control valve 3a opened and gas drawn off until the pressure in chamber A is about one pound below the desired pressure; then valve 3a should be closed and the carbide magazine again lowered to contact the carbide with the water (Fig. 2).

When the generator is generating acetylene fast enough to operate an extra heavy welding tip the water level in the generating 50 chamber A will be raised so as to act on more carbide as indicated in Fig. 4. When the torch is being operated full blast, if the torch is shut off, the water level inside the generating chamber A is almost instantly lowered by the pressure building up in said chamber 55 and forcing the water below the carbide (Fig. 3) then the carbide dries off. The water will hold its position under such pressure just below the lower end of the carbide magazine as in Fig. 3.

Perfect operating conditions are obtained with a pressure range of from one to ten pounds. The pressure should not be raised above ten pounds in the ordinary apparatus.

65 The carbide magazine may be removed

from the neck at any time; making it perfectly safe to transport the generator and the carbide in the magazine can be used later by replacing the carbide magazine in place.

The generator will produce gas at an almost absolutely uniform gas pressure regardless of the rate at which the gas is being drawn off, due to the fact that the slightest variation in gas pressure in the generating chamber instantly varies the water level, and as the carbide magazine is stationary, variation in water level determines the amount of carbide that is immersed, and the water under the gas pressures automatically accurately adjusts itself to supply gas as needed. 70

This also gives the operator full control of generation at all times by either opening or closing the valve on the torch or tip; and this also eliminates the danger of over generation by over supply of carbide which is common to 75 the ordinary generators.

After this initial generation of gas the required pressure for operating any make of torch or any size of tip may be obtained when desired as follows: To increase the pressure in chamber A the pressure control valve 3a should be first opened so as to connect the generating chamber A with the compression chamber B. This equalizes the gas pressures therein and allows the water in the two 25 chambers to again come to the same level (as in Fig. 1) and the water rising in the generating chamber again reaches the carbide in the magazine, and generation of gas proceeds. When the pressure in chamber A reaches about one pound below that desired, the valve 3a should be closed and the generation of gas will continue at such pressure until the outflow of gas from chamber A is checked, whereupon accumulated pressure 35 will leave the water in said chamber, as in Fig. 3 and generation will cease until the pressure is relieved.

To lower the pressure, the carbide magazine is raised above the water level, as shown 40 in Fig. 1; and the pressure control valve 3a opened and gas drawn off until the pressure in chamber A is about one pound below the desired pressure; then valve 3a should be closed and the carbide magazine again lowered to contact the carbide with the water (Fig. 2).

When the generator is generating acetylene fast enough to operate an extra heavy welding tip the water level in the generating 50 chamber A will be raised so as to act on more carbide as indicated in Fig. 4. The water will hold its position under such pressure just below the lower end of the carbide magazine as in Fig. 3.

Perfect operating conditions are obtained with a pressure range of from one to ten pounds. The pressure should not be raised above ten pounds in the ordinary apparatus.

65 The carbide magazine may be removed

turned end extending into the lower portion of the neck and adapted to adjustably support the carbide magazine therein.

2. In an acetylene gas generator of the character specified; comprising a tank adapted to contain water, a neck portion extending above the top of the tank and having an extension below the top and within the tank; a removable carbide magazine within said neck comprising a cylinder and a series of rods connected to the lower end of the cylinder and forming a basket to retain the carbide and permit access of water thereto, and an adjustable rod entering the tank and extending through the water below the lower end of the neck extension, and having its lower portion upturned within said neck and provided with a basket to support the magazine.

20 3. An acetylene gas generator of the character specified; comprising a tank adapted to contain water, a neck extending upwardly beyond the top of the tank and having an extension depending within the tank below the water level, a closure for said neck, a movable carbide magazine in said neck comprising a cylinder and a series of rods connected to the lower end of the cylinder depending therefrom and forming a basket to retain the carbide in the lower end of the cylinder and permit access of water, and means for vertically adjusting said magazine in the neck.

4. An acetylene gas generator of the character specified; comprising a tank adapted to contain water, a neck extending upwardly beyond the top of the tank and having an extension depending within the tank below the water level, a closure for said neck, a removable carbide magazine in said neck; comprising a cylinder a series of rods connected to the lower end of the cylinder depending therefrom and forming a basket to retain the carbide in the lower end of the cylinder and permit access of water thereto, a cover for the cylinder having a slot and pin engagement; and means for vertically adjusting said magazine in the neck.

5. An acetylene gas generator of the character specified; comprising a tank adapted to contain water, a neck extending upwardly beyond the top of the tank and having an extension depending within the tank below the water level, a closure for said neck, a movable carbide magazine in said neck comprising a cylinder and a series of rods connected to the lower end of the cylinder depending therefrom and forming a basket to retain the carbide in the lower end of the cylinder and permit access of water and an adjustable rod entering the tank and extending through the water below the lower end of the neck extension; said rod having an upturned end extending into the lower portion of the neck and adapted to support the carbide magazine therein.

6. In an acetylene gas generator of the character specified; a tank adapted to contain water; a neck portion extending above the top of the tank and having an extension below the top and within the tank; a removable carbide magazine within said neck comprising a cylinder adapted to retain the carbide and permit access of water thereto at its lower end; and an adjustable rod entering the tank and extending through the water below the lower end of the neck extension, and having its lower portion upturned within said neck and provided with a basket to support the magazine.
